CLAIM

The ornamental design for a display screen or portion thereof with graphical user interface, as shown and described.

DESCRIPTION

FIG. 1 is a front view of a display screen or portion thereof with graphical user interface, showing a first embodiment of the new design; and,

FIG. 2 is a second embodiment thereof.

The outermost dashed broken lines in FIGS. 1-2 show a display screen or portion thereof, and form no part of the claimed design. The other dashed broken lines in FIGS. 1-2 show text, graphics, and other elements of the graphical user interface that form no part of the claimed design.

1 Claim, 2 Drawing Sheets
